No. 748,927.

PATENTED JAN. 5, 1904.

B. B. CARLISLE & J. R. ELDER.
EMERGENCY CAR COUPLING.

APPLICATION FILED OCT. 30, 1903.

NO MODEL.

UNITED STATES PATENT OFFICE.

BRYANT B. CARLISLE AND JOHN R. ELDER, OF COLUMBUS, OHIO, ASSIGNORS
OF ONE-THIRD TO L. D. HAGERTY, OF COLUMBUS, OHIO.

EMERGENCY CAR-COUPLING.

SPECIFICATION forming part of Letters Patent No. 748,927, dated January 5, 1904.

Application filed October 30, 1903. Serial No. 179,173. (No model.)

To all whom it may concern:

Be it known that we, BRYANT B. CARLISLE and JOHN R. ELDER, citizens of the United States, residing at Columbus, in the county of 5 Franklin and State of Ohio, have invented a certain new and useful Improvement in Emergency Car-Couplers, of which the following is a specification.

Our invention relates to the improvement 10 of emergency car-couplings, and has particular relation to the improvement of the construction set forth in our former application for patent, Serial No. 165,808, filed July 16, 1903.

15 The objects of our present invention are to provide an improved emergency car-coupler which may be utilized for the purpose of connecting cars from which one or more draw-bars or coupler-heads have been broken or 20 in which the draft-timbers have been pulled out or displaced, to provide an improved construction of yoke for embracing the king-bolt of a car, to so construct our improved coupler as to permit of such lateral movement 25 of its sections as to compensate for the movement of the cars with which our device may be connected, and to produce other improvements the details of which will be more fully pointed out hereinafter. These objects we accomplish in the manner illustrated 30 in the accompanying drawings, in which—

Figure 1 is a plan view of our improved coupler, and Fig. 2 is a side elevation of the same.

35 Similar numerals refer to similar parts throughout the several views.

In carrying out our invention we employ an integral yoke-like body 1, the end portions of the parallel arms of which are adapted 40 to be inserted through opening in a transverse bar 2, said yoke-arms being held from voluntary withdrawal from said bar through the medium of pins or keys 3, which are preferably of the wedge shape shown and which 45 are adapted to be inserted in openings in the outer end portions of said yoke-arms. At the center of its length the bar 2 is provided with a channeled lip or lug 4, with which is connected through the medium of a vertical 50 and removable pivot-pin 5 the rear end of a

connecting-bar 6. The forward end of this connecting-bar is likewise pivoted between the jaws 7 of the recessed or bifurcated head of a screw member 8, the latter having its threaded portion adjustably entering one end 55 of a turnbuckle 9. Similarly connected with the opposite end of said turnbuckle is the threaded portion of a screw member 10, corresponding with the member 8 and between the outer end jaws 11 of which is pivoted, as 60 prescribed for the bar 6, a forwardly-extending bar 12, the latter having formed at its outer end on its upper and lower sides opposing bosses 13, through which and the body of the bar 12 is formed a suitable opening 14. 65

In utilizing our device the yoke 1 is first made to embrace the king-bolt of a car which has been injured, after which the forwardly-extending parallel members of the yoke are inserted through the openings in the bar 2 70 and the pins 3 dropped or driven into place. It will be observed that in the formation of the yoke-body 1 we provide upper and lower projecting lugs 1^a and 1^b, which when the yoke is in place are designed to respectively engage 75 the body and truck bolsters of the car. The knuckle being removed from the draw-bar of the adjoining car, the connection of the two cars is made by the insertion of the outer end portion of the bar 12 in the draw-bar 80 of said adjoining car, the enlarged end of said bar receiving the usual knuckle-pin to connect it with the draw-bar.

From the description heretofore given it will be seen that we have simplified the construction of the clamping-yoke and the parts connected therewith and that by the introduction of the pivoted bars 6 and 12 a desirable lateral motion may be attained by the sections forming our coupler, these movements of the parts being deemed necessary to compensate for the slack or movements of the cars toward or from each other. It will be understood that such rotary motion of the parts as may result from the movements of 95 the cars will be attained through the employment of the turnbuckle 9, which, as will readily be seen, may be also utilized in adjusting our improved coupler to various lengths.

Having now fully described our invention, 100

what we claim, and desire to secure by Letters Patent, is—

1. In an emergency car-coupler, the combination with a king-bolt clamp comprising an integrally-formed yoke and a cross-bar detachably connecting the ends of said yoke, of a coupler-body comprising jointedly-connected sections one of which is pivotally connected with said clamp.
- 10 2. In an emergency car-coupler, the combination with a clamp comprising an integrally-formed yoke and a cross-bar detachably connecting the ends of said yoke, of a coupler-body comprising jointedly-connected sections and an intermediate turnbuckle adjustably connected with two of said sections, one section of said coupler-bar having a pivotal connection with the clamp and another section thereof being adapted to receive a coupling-pin.
- 15 3. In an emergency car-coupler, the combination with a clamp adapted to engage a king-bolt, of a turnbuckle and screw mem-

bers adjustably connected with opposite ends thereof, a bar 6 having a pivotal connection 25 with one of said screw members and a pivotal connection with said clamp and a bar 12 having a pivotal connection with the remaining screw member.

4. In an emergency car-coupler, the combination with a clamp comprising an integrally-formed yoke-body and a removable cross-piece connecting the arms of said yoke, said yoke-body having upper and lower projecting lugs, of a coupler-body comprising a 30 turnbuckle, screw members adjustably connected with opposite ends of said turnbuckle, a jointed connection between one of said screw members and said clamp and a bar pivotally connected with the remaining screw 35 member.

BRYANT B. CARLISLE.
JOHN R. ELDER.
